INVENTOR

John W. Bowers

UNITED STATES PATENT OFFICE.

JOHN W. BOWERS, OF FRANKLIN, ASSIGNOR TO THE DOUGLAS AXE MANUFACTURING COMPANY, OF BOSTON, MASSACHUSETTS.

DIE FOR FORMING AXES, &c.

SPECIFICATION forming part of Letters Patent No. 367,131, dated July 26, 1887.

Application filed February 23, 1887. Serial No. 228,461. (No model.)

To all whom it may concern:

Be it known that I, JOHN W. BOWERS, of Franklin, in the county of Norfolk and Commonwealth of Massachusetts, have invented 5 certain Improvements in Dies for Forming Axes and Similar Tools, of which the following is a specification.

My invention relates to the construction of dies to be used in giving finished form to axes 10 and similar wedge-shaped tools, not only upon the sides, but particularly upon the head; and it consists in having the matrix-space in the lower or anvil die contained below a horizontal plane coincident with the striking-surface 15 of that die at the "bit" end equal to the entire finished tool, and the working-face of the upper die when fixed in the machine substantially in a plane parallel with said horizontal plane, while the head-forming face of the lower 20 die is in a plane at right angles to a plane which will bisect the matrix-space laterally. Heretofore dies used for this purpose have been constructed in such manner that a horizontal plane passing laterally through the 25 extreme end of the bit or cutting-edge of the tool as it laid in proper position in the lower or anvil die would divide the tool into equal parts, and the upper surface of the tool would have an inclination equal to the angle made 30 by the plane of such upper surface with said horizontal plane, and the working-face of the upper die must consequently have the same inclination. This construction tends to throw 35 the upper die in the direction of the bit end of the tool every time that that die is forced upon the blank in the anvil-die, which will soon loosen the upper die from its fastenings or cause undue strain upon the machinery.

My improved construction of dies obviates 40 these difficulties, and at the same time gives a much better finish to the head of the tool by pressing it with greater force against the head-forming wall of the matrix.

The drawing forming a part of this specification represents a vertical section of the dies 45 through the middle of the matrix from the head to the bit end, the particular matrix shown being such as will produce an ax; but it will be readily understood that a modification of the specific form of the working-faces

of the dies will produce articles of different external contour, but all within the class of wedge-shaped tools.

As will be seen by reference to the drawing, I make the matrix in the lower or anvil 55 die, A, sufficiently deep and in such form as to bring the upper surface of the tool when placed therein substantially in a horizontal plane passing through the extreme bit end e of the matrix-space or tool; or, more strictly 60 speaking, substantially in a horizontal plane coincident with the striking-surface f of the lower die beyond the bit-forming end of the matrix; and I also make the working-face g of the upper die, B, in a plane, as nearly as 65 its curved surface will admit, which is substantially horizontal and parallel to the plane of the striking-surface f of the lower die. The wall h of the lower die, A, which is to form the head of the tool, I form in a plane at right 70 angles to a plane, i, (shown in dotted line,) which divides the matrix-space into equal parts laterally.

When the upper die is brought into contact with the blank resting in the lower die, the 75 lower inclined face of the matrix therein will cause the blank to be forced toward the head-forming wall h, and thus the head of the tool will be swaged into a smooth and perfect surface, and the edges and corners of the head 80 will be "squared up" and brought into perfect shape at the same time that the sides or cheeks of the tool are given their finished form; and it will also be readily seen that the working-face g of the upper die being sub- 85 stantially in a horizontal plane when striking the upper side of the blank, which occupies substantially a similar plane, will not be subjected to any undue lateral strain, as in the case of dies of prior construction, where two 90 inclined surfaces are brought violently together.

In the construction of the lower die the projecting portion, which constitutes the head-forming wall h, should be made higher than 95 the thickness of the head of any tool which is to be formed therein, in order that when the upper die descends the head end of its working-face may pass below the upper surface of this projecting portion of the lower die and 100

prevent the possibility of crowding the metal of the blank over upon it.

A slight variation of the plane of the working-face of the upper die from a horizontal position will not materially affect the beneficial operation of the dies; but by as much as the angle of inclination between the plane of the working-face of the upper die and a horizontal plane decreases, by so much will the benefits incident to my improved construction be derived.

I claim—

The improvement in dies for forming axes and similar wedge-shaped tools, hereinabove described, in which the working-face of the

upper die is formed substantially in a plane which is horizontal when the die is in proper position in the machine where it is to operate, and the matrix-space equal to the entire finished tool is contained in the lower die below a horizontal plane coincident with the striking surface of the die at the bit end, the head-forming wall of the lower die being at right angles to a plane which will bisect the matrix-space laterally, substantially as shown and described.

JOHN W. BOWERS.
